UNITED STATES PATENT OFFICE

JEAN V. GIESLER, OF KNOXVILLE, TENNESSEE, ASSIGNOR TO THE FULTON SYLPHON COMPANY, OF KNOXVILLE, TENNESSEE, A CORPORATION OF DELAWARE

TEMPERATURE REGULATOR

Application filed April 19, 1928. Serial No. 271,283.

This invention relates to valve mechanism for temperature regulators and more particularly to thermostatically controlled valve mechanism for regulating the flow of cooling medium in the cooling systems of internal combustion engines whereby the operating temperature of the latter is controlled.

It is an object of this invention to provide improved thermostatically controlled valve mechanism whereby the flow of medium may be controlled in a plurality of passages in succession.

Another object of this invention is to provide a device of the character just described embodying an extensible and collapsible corrugated wall adapted to expand throughout its length in opposite directions and having valves operatively associated with the opposite ends thereof.

Another object of this invention is to provide valve mechanism of the type last referred to wherein a main valve and a by-pass valve are adapted to be operated in succession.

Another object of this invention is to provide a thermostatically controlled valve mechanism embodying a bellows thermostat and a pair of valves wherein one valve is adapted to be moved by expansion of the bellows and the other valve is adapted to be moved thereafter by expansion of the bellows.

A further object is to provide a unitary structure of the character just referred to embodying a main valve and a by-pass valve, one of said valves being adapted to be actuated at a lower temperature than the other valve.

A further object of the invention is to provide a device of the above character embodying a main valve and a by-pass valve in which the weight of the valves and thermostat is balanced against the pressure of the circulating medium which tends to open the main valve.

Other objects relate to the provision of thermostatically controlled valve mechanism of the above character which is sensitive and certain in action, inexpensive, and easily installed without special tools or fittings.

Two embodiments of the invention are

shown in the drawings, but it is to be understood that other embodiments are possible, and that the disclosure in the drawings is for the purpose of illustration only, and the scope of the invention is not limited to the specific structures disclosed, but is defined by the claims appended to the specification. 55

In the drawings, wherein like reference characters designate similar parts in the several views:—

Fig. 1 is a vertical mid-sectional view of the device assembled in operative position;

Fig. 2 is a perspective view of the device removed from its mounting;

Fig. 3 is a disassembled perspective view 65 of the device;

Fig. 4 is a vertical mid-sectional view of a second embodiment of the invention;

Fig. 5 is a perspective view of this embodiment removed from its mounting; and 70

Fig. 6 is a perspective view of the lower portion of this embodiment and a portion of the valve seat with which it is adapted to operate.

In the form shown in Fig. 1 of the drawings, the valve mechanism constituting the subject matter of the present invention is mounted on a cylinder head casting 4 having an integral cylindrical extension 5 constituting part of the water jacket of an internal combustion engine (not shown). The end of the extension 5 is flanged at 6 to cooperate with the flange 7 of a coupling member 8 having the radiator hose connection 9 formed integral therewith. Bolts 10 are adapted to pass through registering openings in flanges 6 and 7 and clamp members 5 and 8 together to form the connection for the flow of the cooling fluid from the cylinder head 4 to the radiator hose, not shown. 80

At the base of the extension 5, an opening 11 is formed in the cylinder head casting and extends downwardly through the cylinder jacket to the inlet opening of the usual circulating pump of the internal combustion engine, thus forming a by-pass for the cooling fluid which when open allows the fluid to circulate without passing through the radiator. 95

The thermostatic controlling device is 100

mounted in the extension 5 above the opening 11 and comprises a main valve seat 12, shown as carried by a ring 13 clamped between the flanges 6 and 7 by bolts 10 passing through registering openings therein, or the ring 13 may itself form the valve seat. The main valve seat 12 is here shown as provided with depending arms 14 which support a guide and stop member 15 formed integral therewith, or said arms may be formed integrally with the ring 13.

The valve disk 16 is adapted to engage the seat 12 and is attached in any suitable manner to the valve stem 17 which has a sliding fit within the guide and stop 15 and is attached at its lower end to a bellows head 18. The bellows head 18 is secured to the upper end of a flexible wall or bellows 19 and is sealed thereto in any suitable manner as by soldering. The opposite end of the flexible wall or bellows 19 is attached in any suitable manner as by soldering to a lower head 20 which is adapted to act as a valve to control the opening of the by-pass 11.

25 The valve disk 16 may be provided with a bleeder opening 32 to allow the escape of trapped air and to assure sufficient circulation of the medium around the thermostat.

The valve stem 17 may be provided with 30 an opening 21 therethrough permitting the introduction of a thermosensitive fluid within the chamber formed by the flexible wall or bellows 19 and the heads 18 and 20. The opening 21 may be sealed in any suitable way, as by means of a cork 22 and solder 23, as is usual in devices of this character.

The valve seat 12 and ring 13 are provided with registering openings, and a pair of frame members 24 are provided with lugs 40 25 extending through the registering openings and riveted over onto the valve seat to attach the parts rigidly together, or the frame members may be carried directly by the ring 13 either with or without a separate 45 valve seat member suitably secured thereto.

The frame members 24 extend downwardly alongside the bellows and are provided at their lower ends with downwardly extending lugs 26 which extend through openings 50 27 in upwardly extending arms 28 on the lower bellows head 20. The lugs 26 act as guides for the bellows head 20, and the shoulders 29 at the upper end of the lugs 26 act as stops which determine the upper position 55 of the bellows head 20, which also forms a by-pass valve member.

A compression spring 30 is mounted between the stop member 15 and the valve disk 16, and is of sufficient strength to hold the 60 valve 16 open against the weight of the associated parts. Preferably the interior of the bellows is below atmospheric pressure at ordinary temperatures so that the valve 16 is held closed by reason of the excess pressure 65 of the atmosphere thereon, but if the bel-

lows is punctured so that it expands by reason of its inherent resiliency the valve 16 is held open at all temperatures.

The embodiment of the invention disclosed in Figures 4, 5 and 6 of the drawings 70 is similar to that shown in Figs. 1, 2 and 3 except that the compression spring 30 has been omitted, and a leaf spring 31 is attached at its center to the center of the by-pass valve member 20', and engages at its ends the upper end of the by-pass 11'. Notches 31' may be formed in the rim of by-pass 11' to center the spring 31 if deemed desirable.

75 In this embodiment of the invention also the bellows preferably has its inside pressure less than that of the atmosphere at ordinary temperatures, and the normal length of the bellows 19' is such that it will hold the valve 16' open in case the bellows is punctured, the leaf spring 31 holding the arms 28' on the by-pass valve member 20' against the stop shoulders 29'.

80 The operation of the device illustrated in Figs. 1, 2 and 3 is as follows:

85 A charge of thermo-sensitive fluid is sealed 90 within the bellows 19, preferably under a partial vacuum, and the parts are assembled in operative relation as shown in Figure 1 of the drawings. The valve 16 is held in its closed position and the valve 20 is held in its 95 open position by the contraction of the bellows 19 caused by the pressure of the atmosphere. When the engine is started the circulation of the cooling medium therefore takes place through the by-pass opening 11 and none of the cooling medium is allowed 100 to flow through the radiator except the small amount which passes through the bleeder opening 32.

105 When the temperature of the cooling medium reaches a predetermined point, the thermostat becomes operative, and tends to open the valve 16 allowing circulation of the cooling medium through the radiator. The pressure of the spring 30 on the under side 110 of the valve 16 is sufficient to support the weight of the valve and its associated parts, and maintains the arms 28 on the valve member 20 against their stop shoulders 29 until the valve 16 is raised so far that the bellows 115 head 18 engages the guide and stop 15. During this time the by-pass remains entirely open and the temperature is controlled by the position of the main valve 16. If the temperature of the cooling medium rises 120 above this point, however, the bellows 19 continues to expand and the opposite end of the thermostat moves the valve 20 downwardly thereby closing the by-pass opening 11. All the cooling medium will then be forced to 125 traverse the radiator, and the maximum cooling effect will be secured.

130 Upon a lowering of the temperature of the cooling medium, the operation of the valves takes place in the reverse order that is, the

valve 20 is opened first to allow the cooling medium to circulate through the by-pass 11, and upon a further decrease in temperature the valve 16 closes and shuts off the circulation of the cooling medium to the radiator.

If the bellows 19 should become punctured in any way, the partial vacuum within the thermostat will be relieved and the spring 30 will hold the valve 16 open and allow circulation to take place through the radiator. If the bellows 19 does not have inherent resilience to expand upon equalization of exterior and interior pressure the spring 30 may be selected of sufficient strength to open the valve 16 when the bellows is punctured.

The operation of the device illustrated in Figures 4, 5 and 6 is substantially similar to that just described. When the parts are assembled as shown in Figure 4, the thermostat maintains the valve 16' upon its seat, and the arms 28' on the by-pass valve 20' against their upper stops 29'. The leaf spring 31 also maintains the arms on the by-pass valve member 20' against their stops 29', so that the rise in temperature of the cooling medium first opens the valve 16' until the head 18' engages the stop 15'. A further rise in temperature of the cooling medium causes the leaf spring 31 to be compressed by the downward movement of the lower end of the thermostat, and the valve 20' is caused to close the by-pass opening 11'.

In this embodiment of the invention the free length of bellows 19' is preferably sufficient to hold the valve 16' open should the bellows 19' become punctured, so that when the partial vacuum within the thermostat is relieved upon puncture, the expansion of the bellows will maintain the valve 16' in open position and allow circulation of the cooling medium through the radiator, the valve 20' being held open by leaf spring 31.

It will be seen that there is here provided a thermostatically actuated valve mechanism wherein the flow of the cooling medium may be controlled in a plurality of passages in succession in response to different ranges of temperature of the cooling medium. Furthermore, the thermostat is bodily movable, and the main valve and the by-pass valve are connected directly thereto at its opposite ends so that the structure is a simple, compact, unitary device which is economical to construct and readily assembled and installed. While two embodiments of the invention have been illustrated and described, it is to be understood that the invention is not restricted thereto, as the same is capable of receiving a variety of mechanical expressions, while changes may be made in the details of construction, arrangement and proportions of the parts without departing from the spirit of the invention. Reference will therefore be had to the appended claims for a definition of the limits of the invention.

What is claimed is:—

1. In combination, a thermo-sensitive element having a flexible tubular external wall and a valve at each end, means whereby expansion of the element opens one valve and closes the other, a support for said element permitting it to expand successively in opposite directions and a spring for biasing one of the valves away from its seat, whereby the valves are operated in sequence.

2. In combination, a pair of aligned axially movable valves, a pair of seats limiting the movement of the valves in one direction, a pair of stops limiting the movement of the valves in the opposite direction, an expandable heat sensitive element mounted between the planes of said valves and normally drawing them together, a support for said element, said element being mounted on said support to expand from opposite ends, and yielding means coacting with said element whereby it expands in one direction before it expands in the other.

3. In a thermostatically operated valve mechanism for controlling the flow of cooling medium in the cooling system of an internal combustion engine, a main valve, a by-pass valve, a movable thermostat located between the planes of the valves with its ends mounted thereon and normally drawing the main valve closed and the by-pass valve open, a support for said thermostat permitting expansion thereof throughout its length in opposite directions and resilient means for urging the valves in one direction.

4. In combination, a thermo-sensitive element having an exterior corrugated tubular wall and a valve at each end, means whereby expansion of said element opens one valve and closes the other, a support for said element permitting said element to expand throughout its length in opposite directions, and a spring opposing expansion of said element in one direction whereby said valves are operated in succession.

5. In combination, a thermo-sensitive element comprising a normally contracted tubular corrugated exterior wall adapted to expand throughout its length in opposite directions and having a valve at each end, and a spring opposing expansion of said element in one direction whereby the valves are operated in sequence.

6. In combination, a thermo-sensitive element having a flexible tubular external wall and a valve at each end, means mounting said element whereby it may expand successively in opposite directions, and yielding means whereby expansion of the element operates the valves in sequence.

7. In combination, a thermo-sensitive element having a flexible tubular external wall and a valve at each end, means whereby expansion of said element operates said valves, a support for said element, said element be-

- ing expansible in opposite directions with respect to said support, and means opposing expansion of said element in one direction until said element has expanded in the opposite direction.
- 5 8. In combination, a thermo-sensitive element having a corrugated lateral wall expansible on increase in temperature and provided with a valve at each end, means where-
10 by expansion of the element operates said valves, a support for said element, said ele-
ment being expansible in both directions and throughout its length with respect to said support, and a spring tending to move one
15 of the valves away from its seat, whereby said valves are operated in sequence.
9. In combination, a pair of aligned axially movable valves, an expansible heat sensitive element connected to said valves and dis-
20 posed between the planes of the same, a sup-
port for said element providing an abut-
ment, said element being mounted on said support to expand successively in opposite directions as the temperature rises, and
25 means normally urging said element against said abutment.
10. In a thermostatically operated valve mechanism for controlling the flow of cooling medium in the cooling system of an in-
30 internal combustion engine, a pair of valves, a thermostatic having a normally contracted corrugated tubular wall connected at its op-
posite ends to said valves, a support for said thermostatic, said thermostatic being mounted
35 on said support to expand successively in op-
posite directions, and means normally urg-
ing said thermostatic in one direction.
11. Apparatus of the class described com-
prising a normally closed main valve, a nor-
40 mally open by-pass valve, a thermostat in-
cluding an extensible bellows for actuating said valves, a support for said thermostat, said thermostat being mounted on said sup-
port to expand successively in opposite di-
45 rections as the temperature rises, and means whereby an equalization of the pressures in-
side and outside the bellows will open the
main valve and a positive pressure within
the bellows will close the by-pass valve.
- 50 12. In combination, a thermo-sensitive ele-
ment having a normally contracted flexible tubular wall, a valve connected thereto at each end thereof, a support for said ele-
ment, said support cooperating with said
55 element to provide an abutment and said element being mounted on said support to expand successively in opposite directions, and a spring cooperating with said element to aid the expansion thereof in one direction
60 upon increase in temperature.

In testimony whereof I have signed this specification.

JEAN V. GIESLER.
